US00D724505S

(12) **United States Design Patent**
Schroeder et al.

(10) **Patent No.:** US D724,505 S
(45) **Date of Patent:** ** Mar. 17, 2015

(54) **FRONT BUMPER FOR AN ALL-TERRAIN VEHICLE**

(71) Applicants: **Anthony Schroeder**, Huntington Beach, CA (US); **Eric Chin**, Irvine, CA (US)

(72) Inventors: **Anthony Schroeder**, Huntington Beach, CA (US); **Eric Chin**, Irvine, CA (US)

(73) Assignee: **Honda Motor Co., Ltd.**, Tokyo (JP)

(**) Term: **14 Years**

(21) Appl. No.: **29/490,714**

(22) Filed: **May 13, 2014**

(51) LOC (10) Cl. **12-16**

(52) U.S. Cl.

USPC **D12/171**

(58) **Field of Classification Search**

(57) **CLAIM**

The ornamental design for a front bumper for an all-terrain vehicle, as shown and described.

DESCRIPTION

FIG. 1 is a perspective view of our new invention;

FIG. 2 is a front view thereof;

FIG. 3 is a top view thereof;

FIG. 4 is a right view thereof, a left view being a mirror image thereof;

FIG. 5 is a rear view thereof; and,

FIG. 6 is a bottom view thereof.

The broken lines shown in the drawings illustrate portions of the front bumper for an all-terrain vehicle that forms no part of claimed design.
